UNITED STATES PATENT OFFICE.

BERNHARDT SMYLE AND CHARLES SMYLE, OF BROOKLYN, NEW YORK.

COLLAPSIBLE ICE-CREAM BOX.

1,141,661.

Specification of Letters Patent.

Patented June 1, 1915.

Application filed August 24, 1914. Serial No. 858,286.

To all whom it may concern:

Be it known that we, BERNHARDT SMYLE and CHARLES SMYLE, of Brooklyn, county of Queens, and State of New York, have invented a certain new and useful Improvement in Collapsible Ice-Cream Boxes, and do hereby declare that the following is a full, clear, and exact description thereof.

Our invention relates to collapsible paper boxes in general, but it has special reference to collapsible boxes used for holding ice cream.

The object of our invention is to provide a box of this character in which the box may be readily folded up by the retailer of ice cream, and again unfolded by the purchaser of the ice cream so as to hold the block of ice cream contained therein in flat position after unfolding so as to enable the same to be readily cut into cakes of the proper size to be served to individuals.

A further object of our invention is to provide a box of the above character in which there are no pasted parts.

25 A further object is to provide such a box which may be readily cut out of a flat sheet of pasteboard or paper, and which may be readily shipped flat, and which does not require any more paper than previous forms 30 of ice cream boxes.

A further object is to provide such a box in which, when the box is folded up, the box holds its required form both when the lid is open and when the lid is closed, and, furthermore, to construct the box in such a manner that the same slots for receiving a tongue to hold the box in the required form while the lid is open, also serve to hold the tongue of the lid when the lid is closed.

40 While our invention is capable of embodiment in many different forms, for the purpose of illustration we have only shown one form thereof in the accompanying drawings, in which—

45 Figure 1 is a plan view of one of the box blanks ready to be folded up; Fig. 2 is a perspective view of a box folded up but with the lid open; and, Fig. 3 is a perspective view of the box showing the same folded up 50 and with the lid closed.

In the drawings we have shown a box blank having a back A and a front B, said back and front being connected together by a bottom J. Adjacent to the back A are two sides C to which are attached two front flaps D, each of which has a slot E. Each

of the sides C has a lateral top flap H, and between each of the sides C and the bottom J there is a corner fold K. The back A has attached to it a rear top flap I provided with a tongue G. The front B has, furthermore, 60 a tongue F.

As shown in Fig. 2, the parts are folded up in such a manner that the corner folds K overlie the bottom J and the front folds D overlie the front B. When the parts have been moved into this position and the slots E brought into registry, the tongue F attached to the front B is moved into said slots E, whereupon the box is permanently held in its required shape, but with the top flaps H and I open. As shown in Fig. 3, when it is desired to close the lid or top I of the box, the tongue G is inserted in the slots E over the tongue F. When the ice cream which has been placed in the box is to be eaten, the tongue G alone may be removed from the slot E so as to permit the top flaps H and I to be raised from above the top of the box. The box would be operated this way when it would be desired to remove the ice cream as, for example, with a spoon, from the top of the box. When, however, the block of ice cream inclosed in the box is to be removed as a whole or cut up into 70 cakes for individual use, both of the tongues F and G are removed simultaneously from the slots E, whereupon the block of ice cream will be found to lie flat upon the back A, so that it may be readily removed as a whole or cut up into cakes as desired. 75 It is, of course, to be understood that the boxes may be made in any sizes desired.

While we have described our invention above in detail, we wish it to be understood that many changes may be made therein without departing from the spirit of our invention.

We claim:

1. A collapsible box having a bottom, 100 sides, a front and a back all connected together, and having a single tongue and slot connection adapted to hold all of said parts in the shape of a box while the box is open at the top, comprising two registering slots 105 and a single tongue fitting into the slots.

2. A collapsible box having a bottom, 110 sides, a front and a back all connected together, and having a single tongue and slot connection adapted to hold all of said parts in the shape of a box while the box is open at the top, comprising two registering slots and

- a single tongue fitting into the slots, the tongue being attached to the front.
3. A collapsible box having a bottom, sides, a front and a back all connected together and having a single tongue and slot connection adapted to hold all of said parts in the shape of a box, comprising a plurality of overlapping front flaps having slots and a tongue passing through said slots.
- 10 4. A collapsible box having a bottom, sides, a front and a back all connected together and having a single tongue and slot connection adapted to hold all of said parts in the shape of a box, comprising a plurality of overlapping front flaps having slots and a tongue passing through said slots, said tongue being located on the front.
- 15 5. A collapsible box having a bottom, sides, a front, a back all connected together and having a single tongue and slot connection adapted to hold all of said parts in the shape of a box, comprising front flaps having slots and a tongue passing through said slots, and a top having a tongue also fitting in said slots.
- 20 6. A collapsible box having a bottom, sides, a front, a back all connected together, and having a single tongue and slot connection adapted to hold all of said parts in the shape of a box while the box is open at

the top, comprising front flaps having slots and a tongue passing through said slots, and a top having a tongue also fitting in said slots.

- 25 7. A collapsible box having a bottom, sides, a front, a back and a top all connected together, the sides having front flaps with slots and the top having a tongue fitting in said slots.
8. A collapsible box having a bottom, a front and a back directly connected thereto, a top and a tongue directly connected to the front, a tongue directly connected to the top, sides directly connected to the back, and front flaps directly connected to the sides having slots to receive said tongues.

- 30 9. A collapsible box having a bottom, a front, and a back directly connected thereto, a top and a tongue directly connected to the front, a tongue directly connected to the top, sides directly connected to the back, front flaps directly connected to the sides having slots to receive said tongues, and corner folds located between the sides and the bottom.
